UNITED STATES PATENT OFFICE.

CORNELIUS WATSON GUERRANT, OF DANVILLE, VIRGINIA.

DESIGN FOR A TOBACCO-PACKAGE.

SPECIFICATION forming part of Design No. 15,424, dated September 23, 1884.

Application filed July 26, 1884. Term of patent 7 years.

To all whom it may concern:

Be it known that I, CORNELIUS W. GUERRANT, a citizen of the United States, residing at Danville, in the county of Pittsylvania and State of Virginia, have invented a certain new and useful Design for Tobacco-Packages; and I do declare the following to be a full, clear, and exact description of the invention, such as will enable others skilled in the art to which it appertains to make and use the same, reference being had to the accompanying drawing, and to letters or figures of reference marked thereon, which form a part of this specification.

The drawing is a representation of this invention, and is a perspective view.

This design has relation to tobacco-packages; and it consists in the novel **M** shape of the roll, having its straight portions contiguous to each other and in the same plane, as hereinafter shown and described.

In the accompanying drawing the roll of tobacco is illustrated in elongated **M** shape, the middle at *a*, and the intermediate points, *b* and *b*, each between the middle and the end, 25 as shown, in convoluted or **M** form, the straight parts *c* and *d* being brought together contiguous to each other and parallel and in the same plane.

Having described this design, what I claim, 30 and desire to secure by Letters Patent, is—

The design for tobacco-packages, consisting of the elongated **M** form, having its straight portions contiguous and parallel and in the same plane, as shown and described.

In testimony whereof I affix my signature in presence of two witnesses.

CORNELIUS WATSON GUERRANT.
